UNITED STATES PATENT OFFICE.

WILLIAM A. MINOR, OF ROCHESTER, NEW YORK, ASSIGNOR TO LUITWIELER PUMPING ENGINE COMPANY, OF ROCHESTER, NEW YORK, A CORPORATION OF NEW YORK.

DEEP-WELL PUMP.

Application filed January 18, 1926. Serial No. 81,923.

The present invention relates to deep well pumps of the type in which a bucket or piston is supported on a rod operated from a mechanism at the top of the well, and an object of this invention is to so operate the rod that the latter will not be subjected to sudden strains and stresses by the operating mechanism at or near the time of the reversing movements of the rod. A further object of the invention is to give to the piston a movement which will enable the latter to run at high speed and, at the same time, to provide for a uniform delivery of the fluid. A further object of the invention is to provide a deep well pump having a plurality of pistons or rods in which the water or fluid load is effectively shifted from one piston to the other without vibration or shock.

To these and other ends, the invention consists of certain parts and combinations of parts, all of which will be hereinafter described: the novel features being pointed out in the appended claim.

In the drawings:

Fig. 1 is a view in elevation of the upper portion of a pump embodying this invention with parts in section;

Fig. 2 is a view in section of a lower portion of the pump in proximity to the two pumps or pistons;

Fig. 3 is a plan view of a cam which may be employed for securing the results of this invention;

Fig. 4 is an edge view of the cam; and

Fig. 5 is a diagram of the movement curve of the cam.

In the illustrated embodiment of the invention, 1 indicates a frame which may be of any suitable construction supported preferably upon a concrete base 2 and having a pump cylinder or case 3 depending therefrom within a well casing 4. Operating in the pump casing are two buckets or pistons 5 and 6, each provided with a valve 7 which is normally held closed by a spring 8. Connected with the lower piston is a rod 9 which extends upwardly therethrough through the upper piston and through a hollow rod 10 which is connected to the upper end to a reciprocating frame or yoke 11 guided on the main frame 1 while the hollow rod 10 is secured at its upper end to a frame or yoke 12 guided vertically on the frame 1.

Arranged to turn on the frame 1 is the

main shaft 13 which carries two cams 14 and 15, each of which cooperates with a roller 16. Each cam 14 and 15 has a supplemental cam 17 on one side thereof which cooperates with a roller 18 on its slide frame or yoke 11. 60 This supplemental cam 17 is provided in order to assure the descent of the rods in the event they should not descend under their own weight. All of the foregoing parts with the exception of the construction of the cam 65 14 are well-known and may be varied within the terms of the appended claims.

A feature of this invention is to so operate each of the rods that they will not be subjected to sudden strains and stresses at the 70 time of the reversal of their movements and also to give to the piston a movement which will enable the latter to be run at high speed and, at the same time, to provide for a uniform delivery of the fluid. From this also 75 flows the advantage that the pump may be run more economically as to power, because there is no sudden starting and stopping of the pistons at the ends of their movements and because the water delivery is constant. 80

In the present embodiment, the foregoing results have been accomplished by the shaping of the cams 14 and 15, but it will be understood that the invention is not limited to a cam for producing these results as it is 85 apparent that the same results may be accomplished by equivalent mechanical means. Each cam 14 and 15 is, in this instance, shaped as shown in Fig. 3 of the drawings, starting with a low point between the lines 90 $a-b$ which are substantially concentric with the axis of the shaft 13 of the cam. During this portion of the movement of travel of the cam, no movement of the rod or bucket takes place. The cam has a surface $b-c$ which is 95 what may be termed an acceleration curve. This acceleration curve starts the rod and bucket on its first part of ascending movement, first stretching the rod and in effect lengthening the rest period and then starting the bucket to move at its uniform speed. The surface from the point c to a point d is so formed that it maintains the speed of travel of the rod and its bucket at a uniform rate which is maintained until the rod with 100 its bucket approaches the upper portion of its movement. Thereafter, a portion of the cam between the points d and e is brought into operation and this portion acts as a retarding portion which slows down the speed 110

of the rod toward the point *e* which is the uppermost portion of travel of the rod. During the time that the portion *d*—*e* of the cam is operating the rod is shortening in its 5 length or relaxing from the stretched condition which was imposed upon it at the time the portion of the cam *b*—*e* was in operation due to the weight of the rod, the bucket and the water upon the bucket. The 10 amount that this rod is relaxed plus the amount of movement effected by the portion *d*—*e* of the cam is such that the movement of the piston or bucket continued to be uniform or substantially at the same speed that 15 it was moving while travelling the greater portion of the way upward in the cylinder or between the points *c* and *d*. As a result, when the beginning of the point *e* of the cam is reached, the rod will be untensioned or 20 relaxed. From the point *e* to the point *f* the cam has a surface concentric with the axis 13 and acting as a rest period, at which time the rod and the piston momentarily stand still to overcome inertia to prepare themselves for the descending movement. This 25 descending movement is controlled by a surface *f*—*g* on the cam which is so formed that it permits the descent of the rod and its bucket at a gradually increasing speed, so 30 that during the first part of the downward movement or drop the rod descends without any buckling or bending action. From the point *g* to the point *h*, the cam has a surface which controls the descent of the rod at a 35 uniform speed. When the point *h* or the end of the surface *g* is reached, another retarding action is imposed upon the rod. This is effected by the surface between the points *h* and *a*. This retarding action slows up the 40 rod and its bucket so as to permit the rod again to relax and, at the same time, to place it in condition for stopping when the lower rest period *a*—*b* is reached again.

The lower point of the cam is not diametrically opposite the high point so that, 45 when the two cams are brought into operation, there is an overlap period which permits an easy transfer of the water load from one piston to the other. This overlap period from one piston to the other occurs between the points *a* and *i* on the surface of the cam when the cams are spaced 180° apart as shown. That the uniformity of the flow of the pump will be apparent, reference is had 50 to the diagram illustrated in Fig. 5. In this diagram it will be noted that the velocity curve is straight or uniform or both at the upward and the downward motion, except at the ends and the high point of the diagram.

In pumps of this type, the water load on the pistons reaches considerable proportions often as much as 8000 pounds or more per piston. With this amount of load hanging

on the end of three or four hundred feet of 65 sucker rod, there is a great deal of elongation in the rod on its power stroke and this has heretofore been released with violence because the load has been relieved suddenly. This factor alone has been the cause of rapid 70 wear and operating difficulties and has only been eliminated by reducing the speed of the driving mechanism. Another difficulty encountered heretofore has been caused by the lack of control of the inertia of the rods 75 due to their great weight and velocity in one direction. This has been heretofore suddenly reversed at the upper end of the stroke by the supplemental cam which received the shock of the upward movement, and then 80 suddenly started the rod with the piston in the opposite direction, the reversal at the lower part of the stroke being effected by the main cam and under like conditions. Furthermore, the operation of the pump could 85 only be effected by running the pump at a slow speed for if the pump were running at a high speed the momentum of the pistons and rods would cause the latter to jump off the cams producing the pumping action and 90 cause the destruction of the cams as a whole. This difficulty could be overcome to some extent by changing the shape of the cam, but this had the effect of making it impossible to obtain a uniform delivery of the fluid load, 95 thus reducing the amount of water possible to be pumped out of a given well in a given time. It must be recognized that these pumps are expensive apparatus and to be economical must produce the maximum fluid 100 delivery from a given well.

What I claim as my invention and desire to secure by Letters Patent is:

A deep well pump comprising a cylinder, a piston operating therein, a rod connected 105 to the piston and operating mechanism for reciprocating the piston in the cylinder having a cam provided with two surfaces concentric with its axis for producing rest periods at the top and the bottom of the movement of the piston, a surface formed to produce a uniform upward motion, a shorter surface formed to produce a uniform downward motion at greater speed than the upward motion, a retarding surface between the surface producing the upper rest period and the surface producing the upward motion, an accelerating surface between the rest period producing surface and the surface producing the downward motion, a retarding surface between the surface producing the downward motion and the surface producing the lower rest period and an accelerating surface between the surface producing the lower rest period and the surface 110 producing the upward motion.
